IGNITION APPARATUS

James L. Arthur, Anderson, Ind., assignor, by
mesne assignments, to General Motors Corpora-
tion, Detroit, Mich., a corporation of Dela-
ware

Application December 30, 1931, Serial No. 583,907

13 Claims. (Cl. 123—117)

This invention relates to ignition apparatus for internal combustion engines and more particularly to devices for controlling the timing of the ignition in accordance with engine speed and engine load conditions.

5 A centrifugal control which is constructed to give approximately correct timing in response to variations in speed for certain loads will not be correct for other loads. For example a centrifugal control constructed for full load operation will not give sufficient advance for part load operation, and will not provide sufficient retard for engine idling.

It is one of the objects of the present invention to effect a greater spark retard at idling speeds than is possible alone with a centrifugal control constructed to take care of operations at a certain load, preferably full load, in order that the engine will idle more steadily and will not 10 tend to stall. Another object is to obtain a greater spark advance under part load operating conditions than is possible with said centrifugal control alone in order to obtain better fuel economy. In order to accomplish these objects 15 I provide in addition to the centrifugal spark control, a double acting control operated by engine suction. In the disclosed embodiment of the invention I provide a diaphragm dividing a housing into two suction chambers, the diaphragm being held in normal or center position by one or more springs which resist movement of the diaphragm in either direction normally. A suction chamber on one side of the 20 diaphragm is connected with a port in the engine fuel passage the port being located in the proximity to an edge of the throttle valve when closed and being located on the engine side of the valve. The other suction chamber is connected with a port in the fuel intake passage said 25 port being located in proximity to an edge of the throttle valve when closed and on the carburetor side of said valve. When the engine is idling there will be a vacuum in that suction chamber which is connected to the port on the engine side of the throttle valve; and that vacuum will operate to retard the ignition in order 30 to give smooth engine operation while idling. When the engine is operating at part load the suction in the first mentioned suction chamber 35 will be relatively low and hence inoperative to retard the ignition; but the suction in the other chamber connected to the port on the carburetor side of the throttle valve will be operative to advance the ignition to a greater extent than 40 possible with the centrifugal advance alone.

With wide open throttle, the vacuum is very low at either port; hence, neither suction device will be operative to advance or retard the ignition and the timing will be controlled by the centrifugal device alone.

5 Further objects and advantages of the present invention will be apparent from the following description, reference being had to the accompanying drawings, wherein a preferred embodiment of one form of the present invention 10 is clearly shown.

In the drawings:
Fig. 1 is a diagrammatic plan view of the apparatus embodying the present invention certain parts being shown in section taken on the line 15 1—1 of Fig. 4.

Figs. 2 and 3 are charts illustrating the operation of the invention.

Fig. 4 is in part a longitudinal sectional view of an ignition timer to which the present invention, which is shown in side elevation, is attached.

Figs. 5 and 6 are sectional views taken on the lines 5—5 and 6—6 of Fig. 4.

Fig. 7 is a sectional view of a suction operated 25 device which is a modified form of that shown in Figs. 1 and 4.

Referring first to Fig. 4, 20 designates an ignition timer housing having a shank 21 which provides a bearing 22 for an ignition timer shaft 30 23 driven by the engine in any suitable manner. The shank 21 includes a bearing portion 24 received by a well provided by the engine frame 25. The shaft 23 drives a weight plate 26 carrying studs 27 upon which are pivotally mounted 35 weights 28 having arms 29 which cooperate with levers 30 carried by a sleeve 31 which provides an ignition timer cam 32. The weights 28 are urged inwardly toward the shaft 23 by springs 33 attached to studs 27 and to studs 34 carried 40 by the levers 30. One at least of the studs 34 is extended and projects through an enlarged aperture 35 in the plate 26 to act as a rotation stop for the centrifugal mechanism, all as is substantially shown and described in the U. S. 45 Patent No. 1,825,388 to J. T. Fitzsimmons.

Referring also to Fig. 1 the cam 32 engages a rubbing block 40 carried by an ignition circuit breaker lever 41 pivoted at 42 and insulated from ground connections and carrying a contact 43 engageable with a grounded contact 44. The rubbing block 40 is urged toward the cam 32 and current is conducted to the circuit breaker lever 41 by a leaf spring conductor 45 attached at one 50 end to the lever 41 and at the other end to an in- 55

sulated strip 46 connected with an insulated terminal 47. The cam 32 drives a rotor 50 carrying a segment 51 cooperating with distributor posts 52 carried by distributor head 53 which 5 carries a center contact 54 engageable with a button 55 carried by a leaf spring 56 electrically connected to the segment 51 and driven by the rotor 50.

The portion 24 of the timer housing shank 21 10 is embraced by a clamp comprising members 60 and 61 forced together by a screw 62 and a nut 63 which when tightened secures the clamp to the portion 24. The clamp includes an arm 65 carrying a swivel stud 66 through which passes a 15 wire 67 secured to the stud by a screw 68.

A hold-down bracket 70 surrounds the shank portion 24 and is located above the clamp arm 65. The plate 70 is provided with an arcuate slot 71 which receives a screw 72 threaded into the 20 engine frame 25 as shown in Fig. 4. The head of the screw 72 has a shank portion passing through a spring 73 and a washer 74. The spring 73 yieldingly urges the washer 74 and the hold-down plate 70 against a machined surface 76 of the 25 engine frame 25. The plate 70 carries a swivel stud 77 through which passes a wire 78 attached to the stud by a screw 79. The wire 78 passes through a spiral wire tube 80 and hence to a 30 manual control knob or lever in convenient reach of the driver for the purpose of manually adjusting the timing of the ignition. The plate 70 is provided with a notch defined by surfaces 81 and 82 which serve as stops to limit the movement of the swivel stud 66 in either direction 35 when controlled by the suction device which will now be disclosed.

The suction device comprises housing members 90 and 91 the former being attached by screws 92 or otherwise to bracket 93 integral with the 40 plate 70. The bracket 93 is apertured to receive a bushing 94 through which the wire 67 passes, the bushing 94 being secured to the housing 90. The housings 90 and 91 are provided with peripheral flanges 95 and 96 between which the periphery of a diaphragm 97 is clamped, the flange 95 being spun over at 98 against the flange 96 to 45 secure the parts in position. The wire 67 is attached to a rod 100 which is provided with a shank 101 which serves as a rivet to attach to the rod 100 two washers 102 and 103 and between them the diaphragm 97 through which the shank 101 passes. The diaphragm 97 may be made of thin flexible metal or of layers of varnished airplane liner or the like. The housing 91 carries 50 an internally threaded bushing 104 which receives a cap 105 to which a fitting 106 secures a pipe 107. The pipe 107 is connected by fitting 108 with a fuel intake pipe 110 or carburetor frame having a port 111 communicating with the pipe 107. The port 111 is located so that it will be just above the lower edge of the butterfly throttle 55 valve 112 when in closed position indicated at 112a. The valve 112 is carried by a shaft 113 which is manually operated in any suitable manner. The housing 90 carries a threaded bushing 115 to which a coupling 116 secures a pipe 117 secured by coupling 118 to the fuel pipe 110. The pipe 110 carries a port 119 in communication with 60 pipe 117 and located below or on the carburetor side of the valve 112 when in the closed position 112a.

Motion of the diaphragm 97 in either direction is resisted by one spring 120 in the form of invention shown in Figs. 1 and 4. This spring 120

bears at one end against an internal flange 121 provided by sleeve 122 having an outwardly turned flange 123 which is received by shoulder 124 provided integrally by the bushing 104. The spring 120 bears at the other end against a washer 125 5 engaged by the end of the cap 105. The washer 125 fits loosely around the rod 100 and is retained with respect to the rod 100 by a resilient clip 126 having resilient bifurcations 127 received by groove 128 of the rod 100. Movement of the diaphragm 97 toward the right is limited by the flange 123 of sleeve 122 striking the washer 125. Movement of diaphragm 97 toward the left is limited by the washer 125 engaging the flange 123 of the sleeve 122. These stops provided by the elements 123 and 125 are supplemental to the stops 81 and 82 for the swivel stud 66. For convenience of discussion the first may be called inside or diaphragm stops, while the second may be termed outside or distributor stops respectively. By providing the dual set of stops, there is an assurance against rupture or undue stretching of the diaphragm, this being taken care of by the inside stops, which also enables the manufacturer to turn out a structure of uniformity, and there is likewise insured, by the outside stops, means to keep the spark timing relation within certain predetermined limits irrespective of the amount or character of force exerted by the several devices to alter the basic or initial spark timing relation. Either of these sets of stops, or both together, provide for adapting the control devices to the timing adjustment so as to accomplish the maximum efficiency for all conditions of engine operation. It will be appreciated that by use of either or both sets of stops, it is possible to cut off any undesired effect or action of the engine produced suction on the pressure responsive devices. 30

With particular reference to the pressure responsive devices, when the diaphragm 97 moves toward the right, the right hand end of the spring 120 will remain fixed due to the engagement of washer 125 with cap 105; but the left hand end of spring 120 is free to move until flange 123 engages washer 125. When the diaphragm 97 moves to the left the left hand end of the spring 120 will remain fixed due to the fact that it is held by the sleeve 122 while the right hand 45 end is permitted to move until the washer 125 strikes the flange 123 of sleeve 122. In this way a single spring operates to resist movement of the diaphragm 97 in either direction, and to retain the diaphragm normally in a central position as shown in Fig. 1. 55

In the form of invention shown in Fig. 7 two springs 130 and 131 are employed for resisting movement of the diaphragm 97 to the right and to the left respectively. In Fig. 7, the housing 91a corresponding to the housing 91 of Fig. 1 carries a threaded bushing 104a into which is threaded a cap 105a to which the pipe 107 is connected by a coupling 106. The sleeve 122a in this form has its flange 121a engaged by the left hand 60 ends of both springs 130 and 131. The right hand end of spring 130 engages the surface 132 of cap 105a. The right hand end of spring 131 engages the clip 126. Movement of the diaphragm 97 toward the right causes the sleeve 122a to move 65 relative to the bushing 104a thereby compressing the spring 130 between the flange 121a and the bushing surface 132. When the diaphragm 97 moves toward the left the sleeve 122a remains fixed relative to the bushing 104a while the spring 70 75

131 is compressed between the flange 121a and the clip 126.

Where a single spring cannot be calibrated so as to resist the movement of the diaphragm properly in either direction the construction shown in Fig. 7 may be used. As stated before, each spring in Fig. 7 resists movement of the diaphragm in one direction only. However, the mode of operation of either form of invention is the same and that operation will now be described with particular reference to Figs. 2 and 3.

By use of the outside set of stops, the range of spark timing retard and advance can be determined, by the spacing of the surfaces 81 and 82, which cooperating with the swivel stud 66 limit the amount of angular adjustment between the plates 65 and 70 that may be made. The initial spark timing relation that is desired and that proves to be most efficient for the particular engine characteristics, can be accomplished by the variable connection between the swivel stud 66 and the wire 67, which position may be accomplished by means of a jig applied to one of the stops 81 or 82 and the stud 66.

Referring to Fig. 2 the curve *a—b—c—d—e* shows the vacuum at the port 111 as the throttle 112 is opened to increase the speed from zero to 15 or more miles per hour. The curve *f—e—g—h* shows the vacuum at the port 119 as the throttle 30 is opened to increase the speed of the vehicle from 10 miles per hour to maximum. It will be noted that these curves cross at point *e* thus indicating that, at about 15 miles per hour, the suction at the ports 111 and 119 is equal and that this suction is approximately 7 inches of mercury. Therefore the spring 120 may be constructed and arranged so that it will not start to move in either direction until a suction of 7 inches of mercury has been obtained and that the diaphragm 97 will be moved to the fullest extent in either direction when about 14 inches of mercury vacuum exists at either port 111 or 119, the extent of diaphragm movement being determined by the stops. The curve *a—b—c—d—e* crosses the 45 14 inch vacuum line at points *b* and *d* corresponding, respectively, to about 3 and 14 miles per hour. Therefore, as the throttle 112 is moved from closed position into a position to cause the engine to idle at about 3 miles an hour the spark will be retarded from about $7\frac{1}{2}$ degrees, represented by point *j* to minus 10 degrees as indicated at point *k* on the speed-spark advance curve *k—l—m—n—o* of Fig. 3. Then as the throttle 50 is opened wider to give the speed of 10 miles an hour the spark will not be retarded any further because the right hand end of the sleeve 122 will have engaged the washer 125 against the cap 105, or depending on the adjustment of the stud 66 with the wire 67, the stop 82 may be engaged by 55 66. In either event, the retard of spark timing relation is cut off at one extreme of the spark timing range, which is represented in Fig. 3 by the dashed line *k—l*. Between 3 miles and about 14 miles the vacuum increases from *b* to *c* and then decreases from *c* to *d* but the spark retard remains the same as at point *k* as indicated by the line *k—l* in Fig. 3. Then as the throttle 60 is opened still wider to give a speed of about 15 miles an hour the vacuum at port 111 falls off very rapidly to point *e* or to about $7\frac{1}{2}$ inches of mercury vacuum; hence, the spark is advanced back to normal as indicated by the line *l—m* which corresponds to the line *d—e* in Fig. 2. As 65 70 75 the throttle 112 is opened still wider the suction

at port 111 falls off still further and is practically negligible at speeds above 20 miles an hour. As the throttle 112 is opened to give vehicle speeds above 15 miles an hour the vacuum at the port 119 increases until at about 30 miles it has reached a maximum of about 15 inches of mercury as indicated by point *g* in Fig. 2. As the speed increases to between 15 and 30 miles an hour the spark is advanced to a degree which is the sum of degrees of advance obtained by the 10 centrifugal device represented by line *m—o* and the degree of advance effected by the suction at the port 119. Therefore, as the speed increases to 30 miles an hour the spark will be advanced in accordance with the curve *m—n* to give the 15 best spark advance for engine economy. At speeds above 30 miles an hour the vacuum at the port 119 decreases as indicated by the curve *g—h*. At maximum speeds the suction device adds practically no degrees of advance to the degrees of advance effected by the centrifugal device alone, hence the spark curve *n—o* slopes downwardly until it reaches the curve *m—o* at point *o*. The curve *m—n—o* therefore indicates that the spark is advanced relatively rapidly between 10 and 30 miles per hour road torque (meaning the load carried by the engine when propelling a vehicle on a level road), and that the spark is retarded relatively slowly as the throttle is opened to give speeds above about 30 miles per hour. 20 25 30

Due to the characteristics of certain engines it may not be desirable to make use of all of the advance provided by the pressure responsive device, but it will be desirable to eliminate a certain portion of its control such as that at the peak of its pressure curve. It is at this point that the other stop means, either 66 and 81 or 123 and 125, come into effect. Assuming that it is desirable to cut off the control of the pressure responsive device between the speeds of about 18 and 40 miles per hour, so that the advance for that range will be confined to a fixed and uniform increase over the control by the centrifugal device, the ultimate spark timing advance will then follow the curve *m—r—s—o* of Fig. 3, instead of *m—n—o*. In accomplishing this result either one of the stops of either set will arrest movement of the diaphragm at the proper point so that there is no further angular shift between the cam and circuit breaker due to the engine produced pressure, between those selected speeds. When this occurs, the spark timing advance will be controlled in accordance with the flat portion of the curve *r—s*. 40 45 50 55

Thus the present device combining a double-acting suction control with a centrifugal control, provides a complete automatic spark timing control which should require no attention by the driver. The manual control provided by wire 78 can be used in emergency to give additional retard if necessary. For ordinary use the manual control 78 might be eliminated and the plate 70 clamped to the engine frame in the desired position of adjustment. 60

While the form of embodiment of the present 65 invention as herein disclosed, constitutes a preferred form, it is to be understood that other forms might be adopted, all coming within the scope of the claims which follow.

What is claimed is as follows:

1. In apparatus for spark timing control of an internal combustion engine, wherein an engine fuel pipe is in communication with the carburetor and engine cylinder and is provided with a butterfly throttle valve regulatory of the speed of engine 75

operation, the combination with said engine fuel pipe, of a circuit breaker, a driving cam for operating the breaker, and means responsive to engine produced suction for varying the angular relation between the cam and breaker, said means including a suction chamber having communication with a port in the engine fuel pipe located on the engine side of the throttle valve and near an edge of the valve only when the valve is substantially closed, and including a suction chamber having communication with a port in the engine fuel pipe located on the carburetor side of the throttle valve and near an edge of the valve when closed, a common diaphragm influenced by the suction in both chambers, and spring means resisting the movement of said diaphragm in either direction.

2. In apparatus for spark timing control of an internal combustion engine, wherein an engine fuel pipe is in communication with the carburetor and engine cylinder and is provided with a butterfly throttle valve regulatory of the speed of engine operation, the combination with said engine fuel pipe of, a circuit breaker, a driving cam for operating the breaker, and means responsive to engine produced suction for varying the angular relation between the cam and breaker, said means including a suction chamber having communication with a port in the engine fuel pipe located on the engine side of the butterfly throttle valve and near an edge of the valve when closed, and including a suction chamber having communication with a port in the engine fuel pipe located on the carburetor side of the butterfly throttle valve and near an edge of the valve when closed, a common diaphragm influenced by the suction in both chambers, and two coiled springs for resisting the movement of the diaphragm in either direction respectively.

3. In apparatus for spark timing control of an internal combustion engine, wherein an engine fuel pipe is in communication with the carburetor and engine cylinder and is provided with a butterfly throttle valve regulatory of the speed of engine operation, the combination with said engine fuel pipe of, a circuit breaker, a driving cam for operating the breaker, said circuit breaker and cam being arranged in a predetermined angular relation, and means responsive to engine produced suction for varying the angular relation between the cam and breaker, said means including a suction chamber having communication with a port in the engine fuel pipe located on the engine side of the butterfly throttle valve and near an edge of the valve when closed for retarding the ignition timing from a predetermined angular relation during engine idling operation, and including a suction chamber having communication with a port in the engine fuel pipe located on the carburetor side of the butterfly throttle valve and near an edge of the valve when closed for advancing the ignition timing beyond the predetermined angular relations during engine operation under part load condition.

4. In an internal combustion engine wherein fuel is delivered thereto through an engine fuel pipe provided with a butterfly throttle valve, ignition apparatus comprising in combination, a circuit breaker, a driving cam for operating the breaker, and means responsive to engine produced suction for varying the angular relation between the cam and breaker, said means including a suction chamber having communication with a port in the engine fuel pipe located on the engine side of the butterfly throttle valve and

near an edge of the valve when closed, and including a suction chamber having communication with a port in the engine fuel pipe located on the carburetor side of the butterfly throttle valve and near an edge of the valve when closed, and including movable means influenced by the suction in both chambers.

5. A spark timing control for an internal combustion engine wherein an engine intake pipe with a butterfly throttle valve conducts fuel from the carburetor to the engine cylinder or cylinders under pressures inversely proportional to engine speed, characterized by the fact that there is in combination, a circuit breaker, a driving cam for operating the breaker, and means responsive to engine produced suction for varying the angular relation between the cam and breaker, said means including a suction chamber having communication with a port in the engine fuel pipe which port is so located that it will be wholly on the engine side of the butterfly throttle valve and near an edge of the valve when the valve is closed and on the carburetor side of the valve when the same is at least partially open, and including a suction chamber having communication with a port in the engine fuel pipe located on the carburetor side of the butterfly throttle valve and near an edge of the valve when closed, a common diaphragm influenced by the suction in both chambers, and a single coiled spring resisting the movement of the diaphragm in either direction.

6. In apparatus for spark timing control of an internal combustion engine, wherein an engine fuel pipe is in communication with the carburetor and engine cylinder and is provided with a butterfly throttle valve regulatory of the speed of engine operation, the combination with said engine fuel pipe of, a circuit breaker, a driving cam for operating the breaker, said circuit breaker and cam being arranged in a predetermined angular relation, and means responsive to engine produced suction for varying the angular relation between the cam and breaker, said means including a servo-motor device responsive to a vacuum differential, and having two conduits leading therefrom, one of which has communication with a port in the engine fuel pipe located on the engine side of the butterfly throttle valve and near an edge of the valve when closed for retarding the ignition timing from a predetermined angular relation during engine idling operation, and the second of which has communication with a port in the engine fuel pipe located on the carburetor side of the butterfly throttle valve and near an edge of the valve when closed for advancing the ignition timing beyond the predetermined angular relations during engine operation at speeds above idling.

7. In an internal combustion engine wherein fuel is delivered thereto through an engine fuel pipe provided with a butterfly throttle valve, ignition apparatus comprising in combination, a circuit breaker, a driving cam for operating the breaker, and means responsive to engine produced suction for varying the angular relation between the cam and breaker, said means including a servo-motor device responsive to a vacuum differential, having two conduits leading to spaced ports in the engine fuel pipe, and a movable member influenced by the vacuum in either or both of the conduits, one of said conduits having communication with a port in the engine fuel pipe located on the engine side of the butterfly throttle valve and near an edge of the valve when closed, and the other conduit having communi-

- cation with a port in the engine fuel pipe located on the carburetor side of the butterfly throttle valve and near an edge of the valve when closed.
8. In an internal combustion engine having a fuel pipe provided with a throttle valve, and subject to variations in engine produced suction incident to self operation, ignition apparatus comprising in combination, a circuit breaker, a cam for operating the breaker and means responsive to engine produced suction for varying the angular relation between the cam and breaker, said means including a suction chamber having communication with a port in the fuel pipe located on the engine side of the throttle valve and near the edge of the valve when closed, an additional suction chamber having communication with a port in the fuel pipe located on the carburetor side of the throttle valve and near the edge of the valve when closed, and a common diaphragm influenced by the suction in both chambers.
9. In an internal combustion engine having a fuel pipe provided with a throttle valve, and subject to variations in engine produced suction incident to self operation, ignition apparatus comprising in combination, a circuit breaker, a cam for operating the breaker and means responsive to engine produced suction for varying the angular relation between the cam and breaker, said means including a suction chamber having communication with a port in the fuel pipe located on the engine side of the throttle valve and near the edge of the valve when closed, an additional suction chamber having communication with a port in the fuel pipe located on the carburetor side of the throttle valve and near the edge of the valve when closed, and a common diaphragm influenced by the suction in both chambers, the movement of the diaphragm in either direction being resisted by spring means located entirely on one side of the diaphragm.
10. In an internal combustion engine having a fuel pipe provided with a throttle valve, and subject to variations in engine produced suction incident to self operation, ignition apparatus comprising in combination, a circuit breaker, a cam for operating the breaker and means responsive to engine produced suction for varying the angular relation between the cam and breaker, said means including a suction chamber having communication with a port in the fuel pipe located on the engine side of the throttle valve and near the edge of the valve when closed, an additional suction chamber having communication with a port in the fuel pipe located on the carburetor side of the throttle valve and near the edge of the valve when closed, and a common diaphragm influenced by the suction in both chambers, the movement of the diaphragm in either direction being resisted by a single coiled spring located entirely on one side of the diaphragm.
11. In an internal combustion engine having a fuel pipe provided with a throttle valve, and subject to variations in engine produced suction incident to self operation, ignition apparatus comprising in combination, a circuit breaker, a cam for operating the breaker and means responsive to engine produced suction for varying the angular relation between the cam and breaker, said means including a suction chamber having communication with a port in the fuel pipe located on the engine side of the throttle valve and near the edge of the valve when closed, an additional suction chamber having communication with a port in the fuel pipe located on the carburetor side of the throttle valve and near the edge of the valve when closed, and a common diaphragm influenced by the suction in both chambers, the movement of the diaphragm in either direction being resisted, respectively, by two coiled springs, one within the other.
12. In an internal combustion engine having a fuel pipe provided with a throttle valve, and subject to variations in engine produced suction incident to self operation, ignition apparatus comprising in combination, a circuit breaker, a cam for operating the breaker and means responsive to engine produced suction for varying the angular relation between the cam and breaker, said means including a suction chamber having communication with a port in the fuel pipe located on the engine side of the throttle valve and near the edge of the valve when closed, an additional suction chamber having communication with a port in the fuel pipe located on the carburetor side of the throttle valve and near the edge of the valve when closed, and a common diaphragm influenced by the suction in both chambers, the movement of the diaphragm in either direction being resisted, respectively, by two coiled springs, one within the other, and both located entirely on one side of the diaphragm.
13. In an internal combustion engine wherein fuel is delivered thereto through an engine fuel pipe provided with a butterfly throttle valve, ignition apparatus comprising in combination, a circuit breaker, a driving cam for operating the breaker, and means responsive to engine running conditions for varying the angular relation between the cam and breaker, said means including a suction chamber having communication with a port in the engine fuel pipe located on the engine side of the butterfly throttle valve and near an edge of the valve when closed, and including a suction chamber having communication with a port in the engine fuel pipe located on the carburetor side of the butterfly valve and near an edge of the valve when closed, and a common diaphragm influenced by the suction in both chambers, the movements of the diaphragm in either direction being resisted, respectively, by two coiled springs both located entirely on one side of the diaphragm.

JAMES L. ARTHUR.
